HAROLD JOHN TAPLIN, OF KEW, SURREY, ENGLAND, ASSIGNOR TO HAROLD JOHN TAPLIN AND SIEGFRIED HENRY KAUFMANN, OF LONDON, ENGLAND

DISPLAY DEVICE

Application filed May 5, 1930, Serial No. 449,900, and in Great Britain May 7, 1929.

This invention relates to signs or advertising or other display devices adapted to be carried by moving vehicles.

The invention is more particularly applicable to a "stop" signal adapted to be mounted on the rear of an automobile vehicle to indicate to the driver of a following car that the vehicle is about to stop.

According to the invention, in a sign or advertising or like display device adapted to be carried by a vehicle, the display is moved automatically by an inertia device on change of speed of the vehicle. In the specific embodiment of a "stop" signal to which reference has already been made, the warning signal such as the word "stop" will be made visible automatically on retardation of the vehicle either by bringing the display into an exposed position or rocking a mirror to render it visible, or moving an electrical contact to illuminate a lamp or in any other suitable manner.

The invention, however, is not limited to such signals, but may be applied, for example, to advertising devices adapted to give a changing display according to various speeds at which the vehicle may be moved.

The invention includes a variety of means which may be well known per se for rendering the display visible. It may, for example, be applied to a form of box sign having a swinging mirror, the mirror in known manner being translucent so that a source of illumination positioned behind it may be utilized to illuminate the sign at night. The sign might alternatively employ a glass having a figured surface adapted to render the display visible by means of transmitted light by day, and by light undergoing more or less complete

internal reflection by night. Alternatively, a light from a separate source of illumination utilized by night may be transmitted through the glass, the figured surface serving to refract it so as to illuminate the display although the source of illumination is seated off the line of sight.

In the case of a "stop" signal, it is an important feature of the invention to provide a device which can be readily mounted on any suitable existing part of the rear of the ve-

hicle and connected to the existing tail-lamp without requiring special leads to the switch board or battery of the automobile.

The invention is illustrated in a preferred embodiment in Figs. 1, 2 and 3 of the accompanying drawing which illustrate respectively a front elevation, a sectional end view on the line II-II of Fig. 1, and a sectional plan view on the line III-III of Fig. 1.

Fig. 4 illustrates a modification of the sign illustrated in Figs. 1 to 3, and

Fig. 5 a further modification.

Figure 6 is a broken perspective showing the reflector operating mechanism removed from the casing.

Turning now to the form illustrated in Figs. 1 to 3, the sign comprises a box-like casing 1, comprising a rear, base and side walls. The front and top of the casing are provided with means of a sheet metal L-shaped attachment 2, adapted to be secured to the casing 1 by means of ears and screws, such as the screws 3. The front of the cap 2 is cut away to form a window behind which is mounted a glass panel 4, and the top is similarly cut away and backed by a glass panel 5.

The display is comprised by a coloured glass sheet 6 slidden in grooves in the side walls of the casing 1 and having an upper 80 figured surface 7 extending generally over the exposed area. The figuring, however, is cut away to leave clear portions in the shape of letters forming, in the case illustrated, the word "stop".

Beneath the display 6 is pivotally mounted a mirror 8 held in a metallic frame 9 pivoted to rock about a horizontal axis within the casing.

According to the invention the mirror is 90 rocked by an inertia member comprising a horizontal pendulum, shown more particularly in Figure 3. The pendulum comprises a weight 10 carried by an arm 11 mounted to rock about a vertical or substantially vertical 95 axis. The articulation of the arm 11 is provided by means of a transverse bar 12 having recessed ends within which lie the pointed ends of screws 13, 14, forming pivots. The screw 13 is carried by a bracket 14 mounted 100

within the casing. The arm 11 is engaged by a fork-shaped member 11a mounted on the mirror casing 9, in such a manner that when the pendulum 11 swings across the casing the 5 mirror 8 is rocked.

In the form illustrated the pivotal axis of the horizontal pendulum is slightly inclined or biased in order that the pendulum may be so loaded as to resist movement in the 10 operative direction by a slight amount more than the natural inertia of the weight 10, for a reason which will hereinafter appear.

A stop 15 is provided to protect the glass panel 4 from the forward swing of the 15 weight 10. The supporting arm 16 of the casing is articulated to a supporting pillar 17 by means of a joint united by a screw bolt 18, so that the arm 16 can be set up at any desired angle. The pillar 17 is provided at 20 its lower end with any suitable form of clip not shown for attachment to the frame, dumb iron, luggage grid, or the like of an automobile vehicle.

It will be appreciated that if the casing 1 25 is set up horizontally as illustrated, the inertia weight 10 will normally lie in the forward position shown in broken lines in Figure 2 owing to the inclination of the axis of the bar 12. The mirror will then occupy the 30 horizontal position shown in broken lines in Figure 2, and the display 7 will not be visible through the glass front 4 of the sign.

Should, however, the speed of the vehicle 35 diminish, the weight will move forwardly of the vehicle to the position shown in full lines in Figure 2, so that the display 7 will be made visible through the window 4 owing to the inclined position of the mirror 8.

Further, owing to the provision of the 40 figures surfaces in the display 7 it will be rendered visible at night by means of the light projected from the head lamps of a following vehicle, the rays of which, if they reach the display 7, will be wholly or substantially reflected back through the mirror 8 and window 4 by internal reflection from the figured surfaces. The inclination of the axis of rotation of the inertia pendulum is 45 preferably such that the mirror is not moved by the vehicle moving down a descending gradient of one in ten for practical purposes. For gradients steeper than this it will be little disadvantage if the display is actuated to reveal the word "stop", owing to the care which 50 is desirable in descending steeper gradients.

Where it is desired to provide a separate 30 source of illumination at night I may provide, in conjunction with the form described above, an elongated electric lamp 19, covered by a shield 20, and adapted to project its light obliquely on to the figured surface 7. The lamp and shield 20 are, however, off the direct line of daylight entering the upper window 5 and illuminating the display by 65 day, the figured surface in this case serving

to refract the light falling on it obliquely to render it visible by night, whilst leaving free access for daylight to render it visible by day. In this connection it is an important 70 feature of the invention to provide means whereby the lamp 19 may be readily attached to the existing wiring of a car without the necessity of special leads carried to the switch board or battery. For this purpose I provide an adaptor 21, so that both the ordinary tail light 22 and the lead 23 of the lamp 19 may be energized by the cable 24 connecting the adaptor to the battery. By this arrangement the stop sign will always be available for use by night when the tail lamp 22 is lit.

In embodiments where the "stop" sign is combined with a tail lamp and number plate during manufacture, the tail lamp 26, Figure 5, may have a pair of downwardly and laterally directed windows 27, 28, one of 85 which illuminates the number plate 29, and the other the figured surface of the "stop" sign 30.

The invention is of course not limited to the forms described above, for example, the horizontal pendulum may rotate a cylindrical mask of aluminium alloy having the word "stop" cut in it in front of a window, and a lamp be mounted within or behind the mask for night use. In a further modification, the pendulum may operate a switch which may illuminate one or more lamps behind the word "stop", both for day and night use. Where a box sign is used the mirror itself might bear the display and either be illuminated by day through a clear upper window 5, or by a lamp positioned behind the mirror by night, the mirror in this case being of the translucent kind, or one in which the silvering 95 is removed in regular patterns over its surface.

Obviously, other means of carrying the invention into effect will readily occur to those skilled in various arts, depending more or less on the purpose to which the sign may be put, or on the taste of the purchaser. These, and all other forms, are intended to be covered by the present invention in so far as they are covered by the appended claims.

I claim:—

1. In an inertia-operated display device intended to be carried by a vehicle, a display, a pivoted reflector in reflective cooperation with the display, a pivoted inertia weight, and connections between said weight and said reflector such that in one position of the weight the display can be viewed and in another is concealed.

2. In an inertia-operated display device intended to be carried by a vehicle, a display device of figured glass illuminated by daylight, in combination with a pivoted reflector having reflective cooperation with said display device and an inertia weight, movement whereof rocks the reflector.

3. In an inertia-operated display device intended to be carried by a vehicle, a display device in combination with a pivoted reflector having reflective cooperation with said display device, a pivoted inertia weight to rock said reflector, and means to illuminate the display at night.

4. In an inertia-operated display device intended to be carried by a vehicle, a display device of figured glass illuminated by daylight, a pivoted reflector having reflective cooperation with the display device, an inertia weight in connection therewith, and means to illuminate the display at night.

15 5. In a vehicle having a rear light, a display device of figured glass illuminated by daylight, means to illuminate the display by night from said rear light, a pivoted reflector having reflective cooperation with the display device, an inertia weight, and connections between said weight and said reflector whereby movement of the weight moves the reflector.

6. In an inertia operated display device intended to be carried by a vehicle, a casing, an indicia-carrying plate forming one side of the casing, a glass plate forming an adjacent side, a mirror pivotally carried in the casing, and means operated by the changes of velocity of the vehicle for moving the mirror to a position to reflect the rays of light passing from the indicia-carrying plate out through the glass plate.

7. In an inertia operated display device intended to be carried by a vehicle, a casing, an indicia-carrying plate forming one side of the casing, a glass plate forming an adjacent side, a mirror pivotally carried in the casing, a horizontally swinging weight operated by the changes of velocity of the vehicle for moving the mirror to a position to reflect the rays of light passing from the indicia-carrying plate out through the glass plate.

45 8. In an inertia operated display device intended to be carried by a vehicle, a casing, an indicia-carrying plate forming one side of the casing, a glass plate forming an adjacent side, a mirror pivotally carried in the casing, a horizontally swinging weight operated by the changes of velocity of the vehicle for moving the mirror to a position to reflect the rays of light passing from the indicia-carrying plate out through the glass plate, and means preventing said weight from being operated by very slight changes of velocity.

9. In an inertia operated display device intended to be carried by a vehicle, a casing, 60 an indicia-carrying plate forming one side of the casing, a glass plate forming an adjacent side, a mirror pivotally carried in the casing, and means for moving the mirror through an angle of 45°, the rays of light 65 coming through the indicia-carrying plate

being directed out through the plain glass plate in one position of the mirror or reflected directly back in the other position of the mirror.

In testimony whereof I affix my signature. ⁷³
HAROLD JOHN TAPLIN.
